UNITED STATES PATENT OFFICE

2,435,862

WINDOW CLEANING APPARATUS

Smith D. Wilson, Chicago, Ill.

Application September 12, 1944, Serial No. 553,755

1 Claim. (Cl. 15—103)

1

The present invention relates to new and useful improvements in apparatus for cleaning windows and has particular reference to the cleaning of windows having upper and lower sliding sash and for cleaning both the inside and outside of such windows.

An important object of the present invention is to provide an apparatus of this character by means of which both the inside and outside of a window may be cleaned without necessitating the operator leaning out of the window, thereby enabling the window to be cleaned while the operator remains inside of the room.

A further object of the invention is to provide an apparatus of this character which may be easily moved from one window to another without necessitating any dismantling of the parts of the machine.

A still further object is to provide an apparatus of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view with parts broken away and shown in section.

Figure 2 is an end elevational view of the brush equipped end of the machine.

Figure 3 is a side elevational view.

Figure 4 is a fragmentary sectional view taken substantially in the vicinity of the arrowed angular line 4 of Figure 1.

Figure 5 is a fragmentary sectional view taken substantially on a line 5—5 of Figure 3.

Figure 6 is an enlarged top plan view of one of the reversing mechanisms.

Figure 7 is a vertical sectional view through the clutch housing for the reversing mechanism, and

Figure 8 is a top plan view of the vertically adjustable chassis.

Referring now to the drawings in detail wherein for the purpose of illustration I have disclosed a preferred embodiment of the invention, the numeral 5 designates a supporting frame mounted on rollers 6 by means of which the machine may be moved into a desired position relative to the window to be cleaned.

Screws 7 are located in each corner of the frame, the upper ends of the screws being

2

journaled swivelly in a chassis 8 adapted for vertical adjustment through the operation of the screws. Sprockets 9 are formed on collars 10 which are threaded on the screws, the collars being retained against vertical movement by means of brackets 11 carried by the frame 5 and through which the screws 7 are threaded.

An endless chain 12 extends around the sprockets 9 and is operated by a sprocket 13 sleeved and splined or otherwise fitted longitudinally slidable but fixed to rotate therewith on the lower portion of a shaft 14 journaled at one side of the frame and manipulated by a handle 15 located on its upper end.

Accordingly the operation of the chain 12 and the sprockets 9 will cause the simultaneous vertical adjustment of the screws 7 at each corner of the frame 5 and thus vertically adjust the chassis 8 relative to the frame.

15 The chassis 8 includes channeled guides 16 at each side of the machine slidably receiving the legs 17 of a brush supporting frame 18, the frame 18 being slidably outwardly from one end of the chassis 8. The outer end of the frame 18 is

20 formed with a transverse guide 19 in which a carrier 20 is slidably mounted, the carrier having a hollow post 21 rising therefrom in which a screw 22 is positioned, the upper end of the screw being journaled in the upper end of the post 21. 25 The opposite sides of the post 21 are formed with vertical slots 23 through which arms 24 project from a collar 25 threaded on the screw, the arms engaging the sides of the slots 23 to prevent rotation of the collar.

30 The outer ends of the arms 24 extend upwardly to form supports 26 and 27 to which brackets 28 are slidably supported by means of wing nuts 29. The brackets 28 include clamps 30 for securing brushes 31 thereto.

35 To the lower end of the screw 22 is secured a beveled gear 32 engaged with a similar gear 33 slidably keyed on a shaft 34 journaled transversely in the outer end of the frame 18. The shaft 34 is operated by means of a beveled gear 40 at one end thereof through a similar gear 36 secured on the outer end of an extensible shaft 37 which extends longitudinally at one side of the chassis 8. The other end of the shaft 37 extends into a gear housing 38 carried at the

45 inner end of the chassis 8 and is reversibly operated through gears 39 and 40 freely journaled on the shaft, the gears 39 and 40 including clutch heads 41 and 42 engageable in sockets 43 and 44 at the opposite ends of a clutch collar 45 slidably keyed on the shaft 37 and operated by

means of a yoke 46 for selectively engaging the clutch collar with the gears 39 and 40.

The gear 39 is operated through gears 47 and 48 on a countershaft 49, the gear 48 being engaged at one side of a ring gear 50 while the gear 40 is operated through gears 51 and 52, the gear 52 being engaged with the ring gear 50 at a side thereof diametrically opposite from the gear 48, as shown to advantage in Figure 7 of the drawings.

The ring gear 50 is secured to a shaft 53 extending transversely of the machine at the inner end of the chassis 8 and is driven by a belt 54 and pulley 55 from an electric motor 56.

The yoke 46 for slidably actuating the clutch collar 45 is formed on one end of an arm 57 which projects radially from a pin 58 journaled in the top of the gear housing 38. To the outer end of the pin 58 is secured an arm 59 having its outer end provided with a knob or handle 60 for swinging in an arc as shown by the arrow in Figure 6 of the drawings to thereby move the clutch collar 45 into its opposite positions for selectively engaging the gears 39 and 40 with the shaft 37. A spring pressed detent 61 is carried by the handle 60 for engaging in recesses 62 formed in the top of the gear housing 38 to secure the clutch collar 45 in either a neutral position, or in either of its oppositely engaged positions.

A screw 62 also extends transversely of the outer end of the frame 18 and is threaded in a bracket 63 formed as a part of the carrier 20. A beveled gear 64 is secured to one end of the screw 62 and is operated through a similar gear 65 secured to the outer end of an extensible shaft 66 extending longitudinally of the chassis 8 at a side thereof opposite from the shaft 37. The shaft 66 is operated by the shaft 53 through a clutch controlled mechanism similar to that heretofore described for operating the shaft 37, the clutch controlled mechanism for the shaft 66 being mounted in a gear housing 67 and controlled through the handle 68.

The legs 17 of the frame 18 are connected near their inner ends by a cross member 69 through which a screw 70 is threaded, the screw extending longitudinally of the frame 18. The screw 70 is operated by means of a clutch mechanism similar to that provided for the shafts 37 and 66 and contained within the gear housing 71. The clutch mechanism for the screw 70 is controlled by the handle 72.

Should a source of current be unavailable for the electric motor 56 the shaft 53 for operating the several parts of the machine may be operated through a manual crank or handle 73.

In the operation of the device it is moved into a desired position adjacent the window to be cleaned and the brush 31 secured in the clamp

30 at the upper portion of the arm 26 or 27, depending on whether the inside or the outside of the window is to be cleaned. The handle 72 for the clutch mechanism controlling the screw 70 is then moved into the desired position for operating the screw 70 to move the frame 18 outwardly of the chassis 8 so that the brush 31 may be brought into contact with the window, the length of movement, of course, being sufficient to place the brush in position for cleaning the inside or outside of the window, and, obviously, to position the device for outside cleaning the window must be accordingly raised and again lowered for the purpose if the device is located inside the room.

The clutch handles 60 and 68 are then moved into position for operating the shafts 37 and 66 so that the brush may be moved vertically by means of the screw 22, or may be moved horizontally by means of the screw 62.

The chassis 8 and the frame 18 carrying the brush support may be adjusted vertically through the manipulation of the handle 15 for operating the screws 7 through the sprocket 13, chain 12 and sprockets 9.

It is believed the details of construction, operation and advantages of the device will be readily understood from the foregoing without further detailed explanation.

Having thus described the invention, what I claim is:

A window cleaning apparatus comprising a portable base element to be placed in working proximity to a window, a horizontally extensible frame on said base element, means for selectively raising and lowering said frame, means including operating and control means mounted on said frame, including means for extending and retracting the extensible frame, a vertically movable cleaner support mounted to be transversely movable on the outer end portion of the extensible frame, said cleaner support carrying a cleaner element thereon, means for selectively raising and lowering said cleaner support including control means mounted on the frame, and means for selectively moving said support transversely of the frame in either direction including control means mounted on the frame.

SMITH D. WILSON.
